UNITED STATES PATENT OFFICE.

GEORGE S. CRAWFORD, OF CHICAGO, ILLINOIS, ASSIGNOR TO SOPHIE L. WOODS, OF CHICAGO, ILLINOIS.

SIDE BEARING.

Application filed February 28, 1927. Serial No. 171,507.

This invention relates to certain novel and useful improvements in anti-friction bearings, more especially adapted for use as side bearings for railway cars, and consists of 5 the matters hereinafter described and more particularly pointed out in the appended claims.

The invention as shown herein and in its preferred embodiment is a side bearing to be 10 applied to the body bolster, as distinguished from the truck bolster, of a railway car and its novel features of construction render its use of particular advantage when thus applied.

15 The object of the invention is to provide a bearing of the kind of simple and economical construction, in which the anti-friction roller, suspended from the casing, is supported and centered by a novel and improved 20 spring-controlled mechanism, which is efficient in operation, which is readily and easily assembled and in which replacements for wear or breakage may be quickly made.

25 The advantages of the invention will appear more fully as I proceed with my specification.

In the drawings:—

Figure 1 is a view representing a top plan of the bearing.

30 Figure 2 is a view representing a transverse section through the bearing in a plane indicated by the line 2—2 of Figure 1.

Figure 3 is a view representing a longitudinal central section through the bearing 35 shown partially in side elevation.

Referring now to that embodiment of the invention illustrated in the drawings: 10 indicates a casing adapted to be secured to the bottom side of a body bolster 11 in any 40 usual or familiar manner. As shown, the body bolster 11 is inclined at an angle to the horizontal and the base plate 12 of the casing has its top face correspondingly inclined at an angle to the horizontal (transversely of the casing) for attachment to 45 said body bolster. Projecting ears or extensions 13, 13 at the ends of the base plate are provided with bolt holes for securing the casing to the bolster in the manner described.

50 The casing is preferably made hollow with a bottom wall 14 and with integral vertical side members 15, 15 and end members 16, 16. Said bottom wall 14 presents a bearing surface 17 on its bottom side against which an

anti-friction roller 18 is designed to roll. 55 The vertical side and end members 15 and 16 project somewhat below the bearing way or surface 17—the side walls 15 providing side ways 15^a, 15^a to guide the ends 19, 19 of the roller and the end walls 16 providing 60 stops 16^a, 16^a which are curved substantially to the curvature of the cylindrical surface of the roller and merge into the bearing surface 17 on the bottom wall of the casing.

20 indicates a U-bar the legs 20^a, 20^a of which embrace the sides of the casing and the bottom or base member 20^b of which is formed to provide a shaft which extends loosely through a central bearing aperture 19^a in the anti-friction roller. At either side 70 of the casing and mid-way of the ends of the path of travel of the roller 18 are provided apertured flanges or ears 21, 21 which extend outwardly from the side ways 15^a, 15^a of the casing. Reinforcing ribs 22 connect 75 the ends of said flanges or ears 21 to the side walls of the casing, said ribs being spaced on either side of the transverse median plane of the casing to provide room for the legs 20^a, 20^a of the U-bar 20, which legs extend 80 up through the apertures in the flanges or ears 21.

23, 23 indicate hollow blocks located in the apertures of the ears 21 and having flanges 24 which bear on the ears 21. The 85 bottom surface of the flange 24 and the top surface of the ear 21 are formed to provide co-acting curved bearing surfaces 25 so that the block 23 is capable of a limited rocking movement on said flange. The curved bearing surface on the flange 21 is carried up by lugs 26 at the ends of said curved surface to provide stops which will retain the block 24 in its intended position. 90

The legs 20^a of the U-bar extend through 95 apertures in the bottoms of the blocks 24, as clearly shown in the drawings. 27, 27 indicate coiled expansion springs on the legs 20^a of the U-bar 20; said springs are seated at their bottom ends in the hollow blocks 24 and are retained at their upper ends by washers 28 held on the top ends of the U-bar legs 20^a, 20^a by pins 29. 100

The bolster 11 is provided with suitable apertures 11^a, 11^a to receive the upper ends 105 of the legs of the U-bar with their associated coiled springs. Said apertures are elongated in the direction of the length of the casing

to permit a swinging movement of the U-bar in the operation of the bearing as will now be described.

It will be manifest from the foregoing description that the coiled springs 27 will act to force the U-bar upwardly and by it to draw the roller into contact with the wear or bearing surface 17 on the bottom wall 14 of the casing,—this because the coiled springs 27, expanding between the blocks 24 (or the ears 21 with which they are engaged) and the washers 28 at the top ends of the U-bar 20, will act to force said bar upwardly at all times. When the roller 18, by reason of its engagement against a bearing plate on the truck bolster, is caused to roll along the bearing surface 17 towards one or the other end of the casing, this movement will act through the U-bar 20 and the washers 28 to compress the springs 27 in proportion to the distance the roller moves beyond its normal middle position. The base member of the U-bar follows the roller in its movement, as shown by dotted lines in Figure 3, while its upper ends swing in the opposite direction, the U-bar as a whole being pivoted by means of the blocks 24 to swing or rock on the ears 21.

Upon the release of the roller by the bottom bearing plate, the expansion of the springs 27 will act to draw the U-bar upwardly and at the same time to swing it on the ears 21 so as to bring it back to vertical position with the roller centered as in the beginning.

It will be manifest that in case of a break or wear of any of the parts of the bearing, that said parts may be readily removed and replaced without removing the bearing as a whole; for example, to replace the coiled springs 27 either one or both of them, it is simply necessary to remove the pins 29 and the washers 28, whereupon the old springs may be removed and new springs applied.

I claim as my invention:

1. In a side bearing, in combination with a bearing member presenting a bearing surface on one side and being constructed for

attachment to a bolster on its other side, a transversely disposed roller engaged with said bearing surface, a U-bar embracing the sides of said bearing member, said U-bar having a bottom member engaged with said roller, means providing a rocking engagement between said U-bar and said bearing member on an axis extending parallel to but spaced above the bottom member of said U-bar and expansion coiled springs on said U-bar above said bearing engagement acting to draw said roller against said bearing surface.

2. In a side bearing, in combination with a bearing member presenting a bearing surface on one side and being constructed for attachment to a bolster on its other side, rocking blocks mounted on said bearing member at either side of said bearing surface, a transversely disposed roller engaged with said bearing surface, a U-bar having a bottom member engaged with said roller and having leg members extending through said blocks and embracing the sides of said bearing member and coiled springs on the legs of said U-bar acting between said blocks on the ends of said legs of said U-bar.

3. In a side bearing, in combination with a bearing member presenting a bearing surface on one side and being constructed for attachment to a bolster on its other side, a transversely disposed roller engaged with said bearing surface, apertured blocks at the sides of said bearing member, means on said bearing member providing rocking engagement between said blocks and said bearing member, a U-bar having a bottom member engaged with said roller and legs extending through said blocks and embracing the sides of said bearing member, spring retaining devices at the tops of the legs of said U-bar and coiled springs on said legs seated at the bottom ends in said block and engaged at the top ends against said spring retaining devices.

In testimony that I claim the foregoing as my invention, I affix my signature this 11th day of February, A. D. 1927.

GEORGE S. CRAWFORD.
